AERIAL BUCKET TRAMWAY

Elmer J. Lloyd, Worcester, Mass., assignor to The American Steel and Wire Company of New Jersey, a corporation of New Jersey

Application July 11, 1940, Serial No. 344,979

2 Claims. (Cl. 214—60)

This invention relates to aerial bucket tramways of the type used to carry material from a loading point to various positions over a dumping area and there dump the material. One object is to control the dumping operation in a positive manner by the use of a simple and inexpensive arrangement.

A specific example of the invention is illustrated by the accompanying drawings, in which:

Figure 1 is a plan of such a tramway;

Figure 2 is an elevation;

Figure 3 is a detailed top view of the bucket;

Figure 4 is a detailed side view of the bucket;

Figure 5 is a detailed front fragmentary view of the bucket;

Figure 6 is a detailed front view of a device for showing the bucket position;

Figure 7 is a vertical section of Figure 6 taken from line VII—VII; and

Figure 8 is a cross section of Figure 7 from the line VIII—VIII.

More specifically these drawings illustrate a double-reversible bucket tramway of the twin track-cable type. Thus twin cables provide flaring aerial tracks 1 and 2 between which the traction rope 3 travels in the form of an endless loop guided by various sheaves 4, the loop being powered by a drum 5 driven by an electric motor 6. A bucket 7 rides each of the tracks 1 and 2, the traction rope being spaced from the track cables by being positioned between them.

Each bucket has wheels 8 which run on the track cables and is provided with a dumping door 9 closed by a latch 10 and which opens due to the weight of the load in the bucket, upon release of the latch 10. The traction rope is, in each instance, connected to the buckets, the arrangement usually being such that one bucket is at the loading position while the other is at its dumping position. Incidentally the loading position is near the motor 6, a spring bumper 11 being arranged in the path of each of the buckets so as to stop them beneath the loading arrangement 12, these bumpers also functioning to make sure the doors of the buckets are latched shut, the bumpers engaging the buckets by way of their doors for that purpose.

The problem with which the present invention is concerned is that of controlling the latches 10 on the buckets so as to effect dumping at the dumping location. This problem has been attacked by various inventors who have developed various arrangements, but in each instance these have certain inherent disadvantages.

In the case of the present invention, the track-

cables forming the tracks are electrically insulated from the traction rope 3. This may be done in various ways and is easily within the ability of those skilled in the art. The traction rope connects with each of the buckets through electrical insulators 13, this being necessary to isolate the track-cables from the traction rope.

Each bucket has its latch operated by an electric motor 14 of the type which, when constantly powered, will effect movement of a limited extent and which will not be damaged by remaining energized after the movement ceases. An example of such a motor is the so-called "thrustor" which is familiar to everyone. This motor 14 is in each instance electrically connected with the traction rope by a wire 15 and with the track-cables by being grounded to the bucket structure. With this very simple arrangement dumping can be effected as desired simply by establishing an electric circuit through the track-cables 1, the motor 14 and the traction rope 3.

Establishment of this circuit is shown as being effected by way of supply lines 16 connecting with the track-cables and the traction rope and controlled by a switch 17. It is to be noted that although operation of this switch effects unlatching of the doors of both buckets simultaneously, this is unimportant because the loaded bucket will be discharged while in motion traveling away from the loading point and the empty bucket is approaching the loading point.

It is common to provide tramways with a bucket indicator 18 worked through a drive 19 by one of the traction rope sheaves so as to render this indicator responsive to movement of the bucket along the track. Such an indicator ordinarily includes a threaded shaft 20 turned by the drive 19 and working a nut 21 which moves a pointer along an indicator scale. Advantage is taken of this to provide the indicator 18 with a contactor 22 carried by a nut worked by a screw 23 that is insulated from the remainder of the indicator, this contactor being arranged for engagement by the nut 21 when it is moved a distance determined by the position of the contactor 22. Lines 24 are shown as leading from the screw 20 and the screw 23 to establish a control circuit in the lines 16, these lines 24 being the same with which the switch 17 is connected.

With the described arrangement it is possible to adjust the contactor 22 so that each time the bucket arrives at its dumping position automatic dumping is effected. When the switch 17 is used, the operator should use it to close the circuit through the track-cables, latch motor on

the bucket and the traction rope, for a sufficient time interval to make sure that the motor effects complete unlatching. If desired, means may be provided for automatically maintaining the circuit closed definite periods of time.

The system described may be employed with either the double or single reversible tramway which may be constructed with either single or twin track-cables. It is to be understood that the track cables, traction rope and bucket are made of metal and are, therefore, electrically conductive.

I claim:

1. An aerial tramway system including a metal aerial track, a traveling bucket riding said track with a dumping door having a releasable catch provided with an electrically powered control device, a metal traction rope for moving said bucket along said track, the latter and said rope being electrically insulated from each other, means for electrically connecting said device with

said track and said rope as said bucket is moved by the latter, and means for establishing an electric circuit through said track, said device and said rope to control dumping of said bucket.

2. An aerial tramway system including a metal aerial track, a traveling bucket riding said track with a dumping door having a releasable catch provided with an electrically powered control device, a metal traction rope for moving said bucket along said track, the latter and said rope being electrically insulated from each other, means for electrically connecting said device with said track and said rope as said bucket is moved by the latter, and means for establishing an electric circuit through said track, said device and said rope to control dumping of said bucket, the second named means including a contact making means in said circuit that is operatively responsive to the travel of said bucket along said track.

ELMER J. LLOYD.
